[57] CLAIM

The ornamental design for a whirlpool bath tub, as shown.

DESCRIPTION

FIG. 1 is a top perspective view of a whirlpool bath tub showing my new design;

FIG. 2 is an alternate top perspective view thereof;

FIG. 3 is a top plan view thereof;

FIG. 4 is a cross-section taken on line 4—4 of FIG. 3; and

FIG. 5 is a cross-section taken on line 5—5 of FIG. 3. The fragmentary broken line representations of a bathroom island installation in FIGS. 1 and 2 are for purposes of illustration only.
